CASING FOR A COMPUTER TERMINAL

Robert Howard, New York, N.Y., assignor to Centronics
Data Computer Corp., Hudson, N.H.

Filed July 24, 1972, Ser. No. 274,477

Term of patent 14 years

Int. Cl. D14—02

U.S. Cl. D26—5 C

The figure is a perspective view taken from the top, front and right side of a casing for a computer terminal embodying my new design, the left side being a mirror image of the side shown and the rear being plain and unornamented.

The broken line representation of a keyboard is for purposes of illustration only.

I claim:

The ornamental design for a casing for a computer terminal, as shown and described.
